(57) **CLAIM**

The ornamental design for a stand for irrigation components as shown and described.

DESCRIPTION

FIG. 1 is a first top perspective view of a stand for irrigation components, according to my new design;

FIG. 2 is a second top perspective view of the stand for irrigation components;

FIG. 3 is a first bottom perspective view of the stand for irrigation components;

FIG. 4 is a second bottom perspective view of the stand for irrigation components;

FIG. 5 is a front elevational view of the stand for irrigation components;

FIG. 6 is a rear elevational view of the stand for irrigation components;

FIG. 7 is a top plan view of the stand for irrigation components;

FIG. 8 is a left side elevational view of the stand for irrigation components;

FIG. 9 is a right side elevational view of the stand for irrigation components; and,

FIG. 10 is a right side elevational view of the stand for irrigation components in an alternate position shown together with a portion of an irrigation component (i.e., a portion of an irrigation tube).

The broken lines in the figures are for the purpose of depicting portions of the stand for irrigation components that form no part of the claimed design. The additional broken lines in FIG. 10 showing the irrigation component (i.e., the portion of the irrigation tube) are for the purpose of depicting environmental structure and form no part of the claimed design. The bottom plan view of the stand for irrigation components is not included as no claimed portion of the stand for irrigation components is depicted in this view.
